2 SHEETS—SHEET 2.

UNITED STATES PATENT OFFICE.

CLARENCE E. BEACH, OF BINGHAMTON, NEW YORK, ASSIGNOR, BY MESNE ASSIGNMENTS, TO THE GAMEWELL FIRE ALARM TELEGRAPH COMPANY, A CORPORATION OF NEW YORK.

AUXILIARY ALARM SYSTEM.

1,253,335.

Specification of Letters Patent. Patented Jan. 15, 1918.

Application filed September 24, 1914. Serial No. 863,321.

To all whom it may concern:

Be it known that I, CLARENCE E. BEACH, a citizen of the United States, residing at Binghamton, in the county of Broome and 5 State of New York, have invented certain new and useful Improvements in Auxiliary Alarm Systems, of which the following is a specification.

My invention relates to alarm systems having signal boxes connected in a general circuit, and each adapted to transmit a signal identifying that particular signal box, and having one or more groups of so-called auxiliary stations,—a different one of said signal boxes and suitable current supply mechanism being connected to each group of auxiliary stations,—whereby the operation of any one of the auxiliary stations will not only cause its connected signal box to be 10 adjusted for the transmission of its signal, but in addition thereto, will cause the operation of indicating mechanism associated with said signal box so as to indicate which of the auxiliary stations has been operated.

25 Auxiliary alarm systems have, in the past, been devised having such indicating mechanism, and having two sets of batteries associated with each auxiliarized signal box, its connected group of auxiliary stations and 30 indicating mechanism, and said systems have been so arranged that one battery set and a portion of the conductors employed were under constant test, but such former systems have not been so constructed that immediate 35 warning would be given in the event of operative impairment of the current paths and batteries vital to an indication of an operated station.

The principal object of this invention is 40 to provide such an auxiliary alarm and indicator system, having all of the advantages possessed by such systems as have been heretofore constructed, and having the additional advantage of keeping under constant test all 45 batteries and conductors whose condition is vital to causing the operation of the station indicating mechanism from any auxiliary station, so that warning will be immediately given of a break in the conductors or of a 50 weakening of the batteries such as might render the operation of an auxiliary station ineffective to produce responsive action of the indicator mechanism.

Other objects of this invention are re-

ferred to in the following specifications and 55 more particularly pointed out in the claims.

In constructing this invention, any well known form of signal box may be employed, which is provided with electromagnetic mechanism adapted to cause such signal box 60 to be set in motion whenever the magnet thereof is sufficiently energized, and, if desired, comprising means for breaking the circuit connected to said magnet as the result of the operation of said signal box. 65

Any well known form of auxiliary station may be employed which has circuit adjusting mechanism comprising means for normally maintaining a connection between two conductors, and, when operated, for breaking such connection between said conductors and connecting one of said conductors to a third conductor, and, if desired, providing some well known form of answer back mechanism adapted to be brought into operative 70 relation with the conductors connected to the auxiliary station when said station is in operated position. 75

Conductors are provided serially including the normally closed terminals of the 80 auxiliary stations, relay mechanism controlling a suitable alarm, the controlling magnet and the circuit breaking contacts (if used) of the signal box to be controlled, and current supply mechanism so applied as to provide a normal current flow therethrough to maintain the relay mechanism in such condition that any material decrease in said current flow will render said suitable alarm operative, such normal current flow being insufficient to cause effective energization of 85 the starting magnet of the signal box. 90

Other conductors are provided serially including relay mechanism, indicator mechanism magnets, normally open terminals of 95 the auxiliary stations, and a resistance, so connected with the first named conductors and the current supply mechanism that when the relay mechanism, the answer back magnet of any auxiliary station (if used), the 100 indicator mechanism magnets, and the starting magnet of the signal box are connected in series, the resultant current flow through said box starting magnet will be capable of adjusting said signal box for the transmission of its signal and said resultant current flow through the magnet of the indicator mechanism associated with the operated aux- 105

iliary station will be capable of adjusting said indicator mechanism to indicate the operated station.

Current indicating mechanism may be 5 suitably connected in series with the current supply mechanism and any well known alarm devices may be so controlled by the relay mechanism as to accomplish results well understood by those skilled in the art, 10 and in addition thereto, to provide means whereby an alarm will be given whenever the current flow falls below a predetermined value, through impairment either of the current supply mechanism or of the circuit 15 through the conductors connected to the indicator mechanism magnets and normally open contacts of the auxiliary stations.

The resistance connected in series with the indicator mechanism magnets and associated relay mechanism should be such that it will cut down the normal current flow therethrough to such a value as to maintain the relay mechanism in such condition that any material decrease in said current flow 25 will result in causing a suitable alarm to be given.

When it is desired to render the operation of this improved auxiliary alarm and indicator system effective in spite of breaks in 30 any conductor connected to a normally open terminal of an auxiliary station or to an indicator mechanism magnet, relay mechanism is connected between one terminal of the current supply mechanism and two parallel 35 sets of conductors, each serially including normally open terminals and associated indicator mechanism magnets of some of the auxiliary stations and said two parallel sets of conductors are connected to a terminal of 40 the resistance.

When it is desired to provide a separate indicating device for each auxiliary station, each so connected as to be under constant test and so arranged that only one of said 45 devices will be operatively affected upon the operation of any auxiliary station, such devices are provided with magnets having two substantially equal windings, and the normally open terminal of the associated auxiliary 50 station is connected to one terminal of each of said windings, and the conductors communicating with other stations, or with the current supply mechanism, are so connected with the remaining terminal of each 55 of said windings that, when the current flows therethrough from the circuit adjusting mechanism of an auxiliary station, the windings of its associated indicator magnet will act cumulatively, and the direction of 60 current flow through the windings of all other indicator magnets will be such that the windings of each magnet will act in opposition to each other.

Various features of my invention are 65 adapted for use, either separately or in com-

bination with each other, with many auxiliary alarm systems and I do not limit myself to the particular arrangements shown in the accompanying drawings and described in this specification, as many changes 70 in construction and arrangement and the insertion or omission of parts may be made without departing from the spirit of my invention.

For the purpose of more clearly illustrating my invention, I have shown its application to auxiliary alarm systems embodying certain well known apparatus and circuits, in the accompanying drawings, in which:

Figure 1 shows such an auxiliary alarm 80 system with my invention applied thereto.

Fig. 2 shows my invention applied to another form of auxiliary alarm system.

Like characters of reference refer to like parts throughout.

Referring to Fig. 1, 1 is a starting magnet adapted to be so associated with any suitable signal box, that when it is properly energized, it may cause the adjustment of said box for the transmission of a signal 90 therefrom.

2 and 3 are contacts included in the circuit connected to the starting magnet 1, and adapted to be so controlled by the signal box associated therewith that said contacts 95 will be separated as a result of the running of the signal box mechanism for the transmission of a signal.

A, B, C, D, E and F are auxiliary stations, each having a well known form of circuit adjusting means, consisting of a switch arm 4, pivoted at 5, and the free end of which is adapted to engage and connect with the separately insulated contacts 6, 7 and 8.

An answer back or buzzer means is also shown at each auxiliary station, comprising well known mechanism, the construction and operation of which is well understood by those skilled in this art.

A terminal set is shown in suitable relation to the starting magnet 1, and comprises testing battery G, operating battery H, galvanometers I and J, resistance K, alarm controlling mechanism comprising trip relay L and cross relay M, and suitable alarm mechanism N controlled by said alarm controlling mechanism.

Two different types of indicator mechanism are illustrated. In the one connected 120 with stations A, B and C and represented by indicator magnets O, P and Q, each magnet is provided with two substantially equal windings which are so connected that the normal current flow therethrough causes 125 them to act in opposition to each other and hence the indicating device is not operated thereby.

The indicator mechanism S is provided with the indicator magnets 90, 91 and 92 130

connected with stations D, E and F, respectively, and has a dial 75, upon which characters indicative of the different stations may be so placed as to be adapted to be exposed, 5 through a suitable opening, when said dial has been released upon the energization of one or more of the magnets 90, 91 and 92, and is thereupon caused to rotate by means of any suitable driving means indicated by 10 the weight 76. Indicator magnet 90 has the armature structure 78 which normally engages a shoulder 79 on the dial 75 and prevents the rotation of the dial. Similar armature structures 80 and 81 are provided 15 for indicator magnets 91 and 92, respectively, and said structures when in retracted position lie in the path of the shoulder 79. The stop pin 82 is provided at such point in the path of the shoulder 79 that the movement 20 of the dial 75 may be suitably arrested thereby when all of the armature structures are in attracted position. When the armature structure 78 is moved to attracted position, the shoulder 79 will be disengaged and 25 the dial 75 will be allowed to rotate in counter-clockwise direction. If the armature structures 80 and 81 are then in attracted position, the dial will continue to rotate until stopped by engagement of the shoulder 79 with stop pin 82. A handle 77 is shown for restoring the dial 75.

One terminal of the testing battery G is so connected with one terminal of the operating battery H, by the conductor 12, that it 30 may serially coöperate therewith. The other terminal of the testing battery G is connected through the conductor 13 to one terminal of the galvanometer I. The other terminal of the galvanometer I is connected 35 through conductor 14 to one terminal of the magnet 15 of the trip relay L. The other terminal of the magnet 15 is connected through the conductor 16 to one terminal of the starting magnet 1. The other terminal 40 of the starting magnet is connected to the contact 2, and contact 3 is connected, through conductor 17, to the pivot 5 of the switch arm 4, of the circuit adjusting means forming part of auxiliary station F. The conductor 18 connects normally closed 45 contact 6, of the circuit adjusting means forming part of auxiliary station F, with the pivot 5 of the circuit adjusting means forming part of auxiliary station E, conductors 50 19, 20, 21 and 22 similarly connect stations E, D, C, B and A, and conductor 23 connects contact 6 of station A with conductor 12.

The current path from the testing battery G, through conductor 13, galvanometer I, 55 conductor 14, magnet 15, conductor 16, starting magnet 1, contacts 2 and 3, conductors 17, 18, 19, 20, 21 and 22, switch arms 4 and contacts 6 of auxiliary stations F, E, D, C, B and A, and conductor 23, forms a loop, 60 one end of which is connected to the battery

G through the conductor 12, and the other end of which is directly connected to said battery, so that a testing current may normally pass through said loop, and the strength of the battery G is such that the 70 current flow through this loop will be sufficient to hold the armature of the magnet 15 out of contact with its back stop, but said current flow will be insufficient to draw the armatures of the magnet 15, or of the starting magnet 1, to their attracted positions, and said current path therefore forms a loop which will be hereinafter referred to as a test loop. 75

The conductor 24 connects one terminal of the operating battery H with one terminal of the galvanometer J, and the other terminal of said galvanometer J is connected, through the conductor 25, to one terminal of the magnet 26 of cross relay M, and the other terminal of said magnet 26 is connected, through the conductor 27, to one end of winding 28 of indicator magnet O. Conductor 29 connects the other end of this winding to contact 7 of auxiliary station A. 80 Contact 7 of auxiliary station A is also connected by conductor 30 to one end of winding 31 of indicator magnet O, the other end of which winding is connected by conductor 32 to one end of winding 33 of indicator magnet P, the other end of which winding is connected by conductor 34 to contact 7 of auxiliary station B. Contact 7 of auxiliary station B is also connected by conductor 35 to one end of winding 36 of indicator magnet 100 O, the other end of which winding is connected by conductor 37 to one end of winding 38 of indicator magnet Q, the other end of which winding is connected by conductor 39 to contact 7 of auxiliary station C. Contact 7 of auxiliary station C is also connected by conductor 40 to one end of winding 41 of indicator magnet Q, the other end of which winding is connected by conductor 42 to one end of winding of indicator magnet 105 90, the other end of which winding is connected by conductor 43 to contact 7 of auxiliary station D. Contact 7 of auxiliary station D is also connected by conductor 44 to one end of winding of indicator magnet 91, 110 the other end of which winding is connected by conductor 45 to contact 7 of auxiliary station E. Contact 7 of auxiliary station E is also connected by conductor 46 to one end of winding of indicator magnet 92, the other 115 end of which winding is connected by conductor 47 to contact 7 of auxiliary station F.

The current path just described forms a loop from the operating battery H to the contacts 7, of the auxiliary stations A to F 125 inclusive, whereby starting magnet 1 of the signal box, and the indicator mechanism, may be operatively affected, and said current path will hereinafter be referred to as an operating loop. 130

The trip relay L comprises;—the magnet 15 and its associated armature structure 48; back stop 49; armature retractile spring 50; insulating button 51; arm 52, pivoted at 53, 5 and having retractile spring 54; trip arm 55, pivoted at 56, and having lifting spring 57, and carrying contact pin 58, in position to be engaged by the cut away end of arm 52; contact spring 59, arranged to engage 10 with trip arm 55; and contact spring 60 arranged to coöperate with contact pin 58. The construction, arrangement, and operation of the various parts of the relay shown, are well understood by those skilled in the 15 art, and in the interests of brevity will not be herein recited.

It will be seen that this relay is arranged to trip a contact upon complete attraction of its armature, and in this sense is herein 20 referred to as a trip relay.

It will further be seen that the trip relay L is so organized that, under predetermined conditions of the circuit connected to the magnet 15, the armature structure 48 may 25 occupy any one of three definite positions, and this relay is therefore not only a trip relay, but is arranged to maintain any one of three sets of local contact conditions, and in this sense is herein referred to as a three- 30 position relay.

The cross relay M is a three position trip relay similar in construction and operation to the relay L just described.

The terminal set also embodies the alarm 35 mechanism N which comprises the battery 61, the disturbance indicator 62, the fire indicator 63, and the alarm bell 64, all connected to relays L and M as shown, so as to be controlled thereby in a manner well understood 40 by those skilled in the art.

The three-position feature of the trip relay L is utilized by employing this relay as a test relay, so long as the trip arm 55 is in depressed position, to cause the disturbance 45 indicator 62 and the alarm bell 64 to act whenever the current flow through the magnet 15 is less than a predetermined value, and as a trip relay, acting whenever the magnet 15 has been abnormally energized 50 both to cause the operation of the fire indicator 63, and to open the connection between the battery 61 and the contacts controlling the trouble indicator 62.

For the purpose of enabling the condition 55 of the vital current path for indicator mechanism magnets through the operating battery, and operating loop, to be under test, the operating loop is extended from contact 7, of auxiliary station F, through conductor 47' to a terminal of the resistance K, and the other terminal of said resistance is connected through conductor 74 to conductor 23, the resistance K being such that, when the battery H is at normal strength, the 60 current passing through magnet 26 will be

barely sufficient to keep the armature structure 48' in its normal or intermediate position.

In the operation of the system shown in Fig. 1, the parts normally occupy the positions shown, the magnet 15 of trip relay L being sufficiently energized by the current flow from testing battery G through the test loop already described to move and retain the armature structure 48 in its intermediate 75 position so that any interruption in the current path through said test circuit (including the starting magnet 1 and contacts 2 and 3) will be indicated by the disturbance indicator 62 and the alarm bell 64 which will 80 be rendered effective through the retraction of the armature structure 48 into contact with its associated back stop 49, and the strength of said current flow is constantly indicated by the galvanometer I.

A second current path is established from the operating battery H through a portion of conductor 12, a portion of conductor 23, conductor 74, resistance K, conductor 47', contact 7 of auxiliary station F, conductor 47, winding of indicator magnet 92, conductor 46, contact 7 of station E, conductor 45, winding of indicator magnet 91, conductor 44, contact 7 of station D, conductor 43, winding of indicator magnet 90, conductor 42, winding 41 of indicator magnet Q, conductor 40, contact 7 of station C, conductor 39, winding 38 of indicator magnet Q, conductor 37, winding 36 of indicator magnet P, conductor 35, contact 7 of station B, conductor 34, winding 33 of indicator magnet P, conductor 32, winding 31 of indicator magnet O, conductor 30, contact 7 of station A, conductor 29, winding 28 of indicator magnet O, conductor 27, magnet 26, conductor 25, galvanometer J and conductor 24 to the opposite terminal of battery H. The current through this path, however, is insufficient to cause the indicator magnets 90, 91 and 92 to attract their armatures, and 100 indicator magnets O, P and Q do not operate because their windings are now so energized as to act in opposition to each other.

Any interruption of this current path will be indicated by the disturbance indicator 62 115 and the alarm bell 64 which will be rendered effective through the retraction of the armature structure 48' of the relay M into contact with its associated back stop 49', and the strength of said current flow is constantly 120 indicated by the galvanometer J.

The operation of this system in case a fire alarm is sent is as follows:—

Suppose the switch arm 4 at the auxiliary station B is moved from contact 6 until it 125 rests upon contact 8 of said station.

When the switch arm 4 touches the contact 7, while still touching contact 6, a current path will be established from the operating battery H, through conductor 12 to 130

junction with conductor 23; from this junction three parallel paths will exist to contact 7 of station B: first, through conductor 23, contact 6 and switch arm 4 of auxiliary station A, conductor 22 to contact 6 of auxiliary station B, thence through switch arm 4 to contact 7 of said station, which path will be referred to as the path through conductor 23; second, from the junction of conductor 23 with conductor 12, through battery G, conductor 13, galvanometer I, conductor 14, magnet 15, conductor 16, starting magnet 1 of the signal box, contacts 2 and 3, conductor 17, switch arm 4 and contact 6 of station F, conductor 18, switch arm 4 and contact 6 of station E, conductor 19, switch arm 4 and contact 6 of station D, conductor 20, switch arm 4 and contact 6 of station C, conductor 21, and switch arm 4 to contact 7 of station B, which path will be referred to as the path through starting magnet 1, but the resistance of this path through starting magnet 1 is so great in comparison with the path through conductor 23 that substantially all the current from the operating battery H will pass through the path through conductor 23; third, from conductor 23, through conductor 74, resistance K, conductor 47', contact 7 of station F, conductor 47, winding of indicator magnet 92, conductor 46, contact 7 of station E, conductor 45, winding of indicator magnet 91, conductor 44, contact 7 of station D, conductor 43, winding of indicator magnet 90, conductor 42, winding 41 of indicator magnet Q, conductor 40, contact 7 of station C, conductor 39, winding 38 of indicator magnet Q, conductor 37, winding 36 of indicator magnet P, and conductor 35, to contact 7 of station B, which will be referred to as the path through resistance K.

The resistance of this path through resistance K is so high in comparison with that of the path through conductor 23 that the current flow through the indicator magnets 90, 91, 92 and Q is insufficient to effectively energize them.

From the junction of the three parallel current paths at contact 7, the current path continues through conductor 34, winding 33 of indicator magnet P, conductor 32, winding 31 of indicator magnet O, conductor 30, contact 7 of station A, conductor 29, winding 28 of indicator magnet O, conductor 27, magnet 26 of cross relay M, conductor 25, galvanometer J, and conductor 24 to the other terminal of operating battery H, which path will be referred to as the path through magnet 26.

Upon the establishment of the current paths just described, magnet 26 will be powerfully energized, and armature structure 48' will move the arm 52' against the tension of springs 50' and 54', and release the trip arm 55' to cause the disturbance indicator 62 and the alarm bell 64 to act.

It will be noticed that, under the condition just described, winding 36 of indicator magnet P will be in the path through resistance K, while winding 33 of this indicator magnet will be in the path through magnet 26, and the current through winding 33 will be greatly increased, so as to be adapted to cause the indicator magnet P to operate its indicating device.

The current through both windings 31 and 28 of indicator magnet O will also have been similarly increased, but as these windings will still be acting in opposition to each other, this indicating device will not be operated.

When the switch arm 4 ceases to touch the contact 6, the current path through conductor 23 will be interrupted, and therefore the current flow through the path through starting magnet 1 will be greatly increased, and will be sufficient to operatively affect the starting magnet 1, and if the signal box is set, in condition to be responsive to the effective energization of said magnet 1, said signal box would be adjusted for the transmission of its signal.

After said switch arm 4 is moved from contact 7 to contact 8, the magnet 9, of the answer back or buzzer means associated therewith, will be serially included in the path through the starting magnet 1 to contact 7, so that the current passing through said path will cause said magnet 9 to draw its armature 10 an abnormal distance from its back stop 11.

When the connection between contacts 2 and 3 is interrupted (as it should be by the running of the signal box) the path through magnet 1 will be broken, and magnet 9 will therefore be deenergized, and the armature 10 will thus be permitted to move away from said magnet, but said armature in moving away from its magnet will acquire sufficient momentum to carry it against back stop 11, so as to reenergize the magnet 9, through establishing a connection from the path through conductor 23, through contact 6, back stop 11, armature 10, switch arm 4, contact 8, magnet 9, and contact 7, to the current path through magnet 26.

Upon such reenergization of the magnet 9, the armature 10 will be again attracted, breaking its connection with its back stop 11 and setting up a buzzing operation which will continue so long as said switch arm 4 remains on contact 8, and the path through starting magnet 1 is open, and during such buzzing operation the indicator mechanism magnets will be subjected to a pulsating current, which current, however, will not cause improper operation of said indicating mechanism.

If the switch mechanism at a station connected with indicator mechanism S is operated, (as for instance station E) by moving

its switch arm 4 from contact 6 to contact 8, the varied current paths already described will be established with the following changes: the current path through conductor 23 will extend from contact 6 of station B, through switch arm 4 of said station, conductors 21, 20 and 19, and contacts 6 and switch arms 4 of stations C and D, to contact 6 of station E; the current path 5 through starting magnet 1 will end at switch arm 4 of station E; the current path through resistance K will end at contact 7 of station E; and the current path through magnet 26 will begin at contact 7 of station E, 10 and pass through conductor 45, winding of indicator magnet 91, conductor 44, contact 7 of station D, conductor 43, winding of indicator magnet 90, conductor 42, winding 41 of indicator magnet Q, conductor 40, conductor 20 tact 7 of station C, conductor 39, winding 38 of indicator magnet Q, conductor 37, winding 36 of indicator magnet P, conductor 35, to contact 7 of station B, where it joins the current path through magnet 26 25 already described. The current flow through the path through starting magnet 1, will, as previously described, be sufficient to operatively affect the magnets 1 and 15. The current flow in the path through magnet 26 will be sufficient to cause 30 the indicator magnets 90 and 91 to release the indicating dial 75 and allow it to move two steps, under the influence of the weight 76, when it will be stopped by the engagement of the shoulder 79 with armature structure 81 of magnet 92, which will not be effectively energized because it will be in the current path through resistance K, thus causing an indication corresponding with 35 station E.

While the current flow through indicator magnets O, P and Q will be greatly increased, as before, the windings of these magnets will be acting in opposition to each 40 other and hence these indicating devices will not be operated.

Should the operating battery or the continuity of the operating loop be so impaired as to jeopardize the operation of the indicator mechanism, such impairment will permit retraction of the armature structure 48' of the cross relay M to cause operation of the disturbance indicator 62 and alarm bell 64.

In the event of a cross or short circuit 45 between the operating loop and the test loop, if such cross is between either conductors 29, 30, 34, 35, 39, 40, 43, 44, 45, 46, 47 or 47', and the test loop, the indicating mechanism will act in response thereto, and any cross 50 between said loops will cause the cross relay M and disturbance alarm 62 and 64 to act in a well known manner.

Fig. 2 shows this invention applied to a 55 form of auxiliary alarm system which is so constructed and arranged that one break in

the operating loop will not disable any auxiliary station, this invention being also so applied to said system that such a break in the operating loop will not disable any indicator mechanism.

The application of this invention shown in Fig. 2 differs from that shown in Fig. 1 principally in that two cross relays are provided, one at each end of the operating loop, a terminal of each of these cross relays being 70 connected to the same conductor from the operating battery, the other terminals of these relays being connected each to its end of the operating loop.

The contacts of the additional cross relay 80 M' are connected in parallel with the corresponding contacts of the cross relay M, and their control of the circuit of the trouble indicator 62 and alarm bell 64 is similarly under the control of the contacts of the trip 85 relay L. The resistance K is connected from the conductor 23 to the operating loop approximately at the electrical center thereof.

The current path through the test loop is as described in connection with Fig. 1.

The normal test current path from the operating battery is as follows:—from one terminal of operating battery H, through a portion of conductor 12, a portion of conductor 23, conductor 74, resistance K, conductor 47', to junction 83, where the current divides into two parallel paths; one path through the part of the operating loop comprising conductor 37', winding 36 of indicator magnet P, conductor 35, contact 7 of station B, conductor 34, winding 33 of indicator magnet P, conductor 32, winding 31 of indicator magnet O, conductor 30, contact 7 of station A, conductor 29, winding 28 of indicator magnet O, conductor 27, magnet 105 26, conductor 25' to junction 84; and the path through the part of the operating loop comprising conductor 37'', winding 38 of indicator magnet Q, conductor 39, contact 7 of station C, conductor 40, winding 41 of indicator magnet Q, conductor 42', winding 85 of indicator magnet R, conductor 43', contact 7 of station D, conductor 44', winding 86 of indicator magnet R, conductor 87, winding 26' of cross relay M' and conductor 110 25''' to junction 84, where the two parallel paths join. From junction 84 the normal test current path proceeds through conductor 25'', galvanometer J, and conductor 24, to the other terminal of the operating 115 battery H.

Inasmuch as the current through the test loop, and through the two halves of the operating loop in parallel with each other, is such as to cause the magnets 15, 26 and 26' to normally hold their armatures in their intermediate position, it is evident that a break in the test loop, or in either of the two branches of the operating loop, will so affect the corresponding magnet as to cause 130

actuation of the disturbance indicator 62 and the alarm bell 64 as in Fig. 1, while a cross between the operating loop and the test loop will so affect both the magnets 26 and 26' 5 as to cause like operation of disturbance indicator 62 and alarm bell 64.

In applying this invention to such an auxiliary alarm system as that shown in Fig. 1, it is desirable that the resistance of the 10 indicator magnets be kept so low that the battery power required to obtain proper current flow, upon the operation of an auxiliary station at one end of the operating loop, will not be unduly in excess of that required to obtain the proper current flow, upon the 15 operation of an auxiliary station at the other end of said loop; and if, owing to the number and resistance of the indicator magnets provided in a given system, the said excess 20 battery power would be undesirably great, if arranged in accordance with Fig. 1, said indicator magnets should be arranged in two or more parallel paths, as indicated in Fig. 2; it being evident that additional 25 relays and indicator magnets may be connected in as many parallel paths between junction 83 and junction 84 as may be desired, and the use of each additional parallel path will tend to increase the efficacy of all 30 such paths.

Thus, not only is all current supply mechanism and conductors whose condition is vital to causing the operation of a signal box from any one of a number of auxiliary stations 35 kept under constant test, in this auxiliary alarm system, but furthermore the indicator mechanism magnets and connections thereto are kept under constant test, and provision is made for the operation of said indicator mechanism without the employment of 40 separate current supply mechanism therefor.

The features hereinbefore described in detail, and shown in the annexed drawings, 45 whereby the current supply mechanism and conductors whose condition is vital to causing the operation of a signal box from any of a number of auxiliary stations are kept under constant test, are not herein claimed, 50 as same form the subject matter of my co-pending application, Serial No. 863,322, filed Sept. 24, 1914, but what I herein claim and desire to secure by Letters Patent of the United States is:

55 1. In an auxiliary alarm system: a box starting magnet; a plurality of auxiliary stations; indicator mechanism having a plurality of electromagnets; suitable current supply mechanism; circuit connections 60 whereby said current supply mechanism may effectively energize the starting magnet and an indicator mechanism magnet upon the operation of an auxiliary station, and whereby test current insufficient to effectively energize said starting magnet is nor-

mally maintained through said starting magnet, and test current is maintained through said auxiliary stations, connections, indicator mechanism magnets, and current supply mechanism; and alarm mechanism so 70 connected thereto as to be responsive to test current impairment.

2. In an auxiliary alarm system: a box starting magnet; a plurality of auxiliary stations; indicator mechanism having a plurality of electromagnets; suitable current supply mechanism; circuit connections whereby said current supply mechanism may effectively energize the starting magnet 75 and an indicator mechanism magnet upon the operation of an auxiliary station, and whereby test current insufficient to effectively energize said starting magnet is normally maintained through said starting magnet, and test current is maintained 80 through said auxiliary stations, connections, indicator mechanism magnets, and current supply mechanism; and alarm mechanism independent of said box starting magnet so connected to said circuit connections as to 85 be responsive to test current impairment.

3. In an auxiliary alarm system: a box starting magnet; a plurality of auxiliary stations; indicator mechanism having a plurality of electromagnets; suitable current 95 supply mechanism; circuit connections whereby said current supply mechanism may effectively energize the starting magnet and an indicator mechanism magnet upon the operation of an auxiliary station, and 100 whereby a test current path is normally maintained through said starting magnet, auxiliary stations, connections, indicator mechanism magnets, and current supply mechanism; and alarm mechanism so connected thereto as to be responsive to operative impairment of said current path.

4. In an auxiliary alarm system: a box starting magnet; a plurality of auxiliary stations; a test loop connected to said auxiliary stations and including the box starting magnet; indicator mechanism having a plurality of electromagnets; a second test loop connected to said auxiliary stations and serially including the indicator magnets; current supply mechanism for said loops; and alarm mechanism so connected with said loops as to be rendered active by a break in either of said loops.

5. In an auxiliary alarm system: a box 120 starting magnet, a plurality of auxiliary stations, a test loop connected to said auxiliary stations and including the box starting magnet, indicator mechanism having a plurality of electromagnets each having 125 two approximately equal windings, a second test loop connected to said auxiliary stations and including the indicator magnets, current supply mechanism for said loops, and alarm mechanism so connected with said 130

- loops as to be rendered active by a break in either loop.
6. In an auxiliary alarm system: a plurality of auxiliary stations; indicator mechanism having a corresponding plurality of electromagnets each having two approximately equal windings; current supply mechanism; and circuit connections between the current supply mechanism, the indicator magnets, and the auxiliary stations, so arranged that the two windings of each magnet normally oppose each other, and that the operation of any auxiliary station will cause the windings of only the associated indicator magnet to become effectively energized to distinctively indicate the auxiliary station operated.
7. In an auxiliary alarm system: a box starting magnet, a plurality of auxiliary stations, a test loop connected to said auxiliary stations and including the box starting magnet, indicator mechanism having a plurality of electro-magnets, a plurality of other test loops each connected to certain of said auxiliary stations and including certain of said indicator magnets, current supply mechanism for all of said loops, and alarm mechanism independent of said box starting magnet so connected with said loops as to be rendered active by a break in any of said loops.
8. In an auxiliary alarm system: a box starting magnet, a plurality of auxiliary stations, a test loop connected to said auxiliary stations and including the box starting magnet, indicator mechanism having a plurality of electromagnets, a plurality of other test loops each connected to a certain plurality of said auxiliary stations and including a corresponding plurality of said indicator magnets, current supply mechanism for all of said loops, and alarm mechanism operative without effectively energizing said box-starting magnet so connected with said loops as to be rendered active by a break in any of said loops.
9. In an auxiliary alarm system: a box starting magnet, a plurality of auxiliary stations, a test loop connected to said auxiliary stations and including the box starting magnet, indicator mechanism having a plurality of electromagnets, a second test loop connected to said auxiliary stations and so serially including the indicator magnets that said indicator magnets are not effectively energized by the normal current flow through said loop, current supply mechanism for said loops, and alarm mechanism so connected with said loops as to be rendered active by a break in either of said loops.
10. In an auxiliary alarm system: a box starting magnet, a plurality of auxiliary stations; a test loop connected to said auxiliary stations and including the box starting
- magnet, indicator mechanism having a plurality of electromagnets, a second test loop connected to said auxiliary stations and so including the indicator magnets that said indicator mechanism is not operatively affected by the normal current flow through said loop, current supply mechanism for said loops, and alarm mechanism independent of said box starting magnet so connected with said loops as to be rendered active by a break in either of said loops.
11. In an auxiliary alarm system: a box starting magnet, a plurality of auxiliary stations, a test loop connected to said auxiliary stations and including the box starting magnet, indicator mechanism having a plurality of electromagnets, a second test loop connected to said auxiliary stations and so including the indicator magnets that said indicator mechanism is operatively affected by the current flow through said loop when said loops are connected by the operation of any auxiliary station, current supply mechanism for said loops, and alarm mechanism independent of said box starting magnet so connected with said loops as to be rendered active by a break in either of said loops.
12. In an auxiliary alarm system: a box starting magnet; a plurality of auxiliary stations; a test loop connected to said auxiliary stations and including the box starting magnet; indicator mechanism having a plurality of electromagnets; a second test loop connected to said auxiliary stations and so including the indicator magnets that said indicator mechanism is not operatively affected by the normal current flow through said loop, and is operatively affected by the current flow through said loop when said loops are connected by the operation of any auxiliary station; current supply mechanism for said loops; and alarm mechanism independent of said box starting magnet so connected with said loops as to be rendered active by a break in either of said loops.
13. In an auxiliary alarm system: a box starting magnet; a plurality of auxiliary stations; a test loop connected to said auxiliary stations and including the box starting magnet; indicator mechanism having a plurality of electromagnets; a second test loop connected to said auxiliary stations and so including the indicator magnets that said indicator mechanism is unaffected by current flow through said loop only, and is suitably affected by current flow resulting from the establishment of a connection between certain conductors of said loop and the other test loop; current supply mechanism for said loops; and alarm mechanism independent of said box starting magnet so connected with said loops as to be rendered active by a break in either of said loops.
14. In an auxiliary alarm system: a box

starting magnet, a plurality of auxiliary stations, a test loop connected to said auxiliary stations and including the box starting magnet, indicator mechanism having a plurality of electromagnets each having two approximately equal windings, a second test loop connected to said auxiliary stations and so including the windings of each indicator magnet that said indicator mechanism will 5 not be operatively affected by any current flow throughout said loop, current supply mechanism for said loops, and alarm mechanism so connected with said loops as to be rendered active by a break in either of said 10 loops.

15. In an auxiliary alarm system: a box starting magnet; a plurality of auxiliary stations; a test loop connected to said auxiliary stations and including the box starting 20 magnet; indicator mechanism having a plurality of electromagnets each having two approximately equal windings; a second test loop connected to said auxiliary stations and so serially including the windings 25 of each indicator magnet that said indicator mechanism will be operatively affected only by current flow from a point in the second loop which is located between the windings of a magnet, to the first test loop; current 30 supply mechanism for said loops; and alarm mechanism so connected with said loops as to be rendered active by a break in either of said loops.

16. In an auxiliary alarm system: a box 35 starting magnet; a plurality of auxiliary stations; a test loop connected to said auxiliary stations and including the box starting magnet; indicator mechanism having a plurality of electromagnets each having two 40 approximately equal windings; a second test loop connected to said auxiliary stations and so serially including the windings of each indicator magnet that said indicator mechanism is not operatively affected by the 45 normal current flow through said loop, and is operatively affected only by current flow from a point in the second loop which is located between the windings of a magnet, to the first test loop; current supply mechanism 50 for said loops; and alarm mechanism so connected with said loops as to be rendered active by a break in any of said loops.

17. In an auxiliary alarm system: a box starting magnet; a plurality of auxiliary 55 stations; a test loop connected to said auxiliary stations and including the box starting magnet; indicator mechanism having a plurality of electromagnets; a resistance; a plurality of other test loops, connected in 60 multiple with each other and in series with said resistance, each connected to certain of said auxiliary stations, and so including certain of said indicator magnets, that said indicator mechanism will not be operatively 65 affected by the normal current flow through

said loop, and will be operatively affected by current flow through said loop when said loop is connected with the first loop by the operation of any auxiliary station; current supply mechanism for said loops; and alarm 70 mechanism so connected with said loops as to be rendered active by a break in any of said loops.

18. In an auxiliary alarm system: a box starting magnet; a plurality of auxiliary 75 stations; a test loop connected to said auxiliary stations and including the box starting magnet; indicator mechanism having a plurality of electromagnets each having two approximately equal windings; a resistance; 80 a plurality of other test loops, connected in multiple with each other and in series with said resistance, each connected to certain of said auxiliary stations and so including both windings of certain indicator magnets, that 85 said indicator mechanism will not be operatively affected by the normal current flow through said loop, and will be operatively affected by current flow through said loop when said loop is connected with the first 90 loop by the operation of any auxiliary station; current supply mechanism for said loops; and alarm mechanism so connected with said loops as to be rendered active by a break in any of said loops. 95

19. In an auxiliary alarm system: a box starting magnet, a plurality of auxiliary stations, a test loop connected to said auxiliary stations and so including the box starting magnet that said magnet is not 100 effectively energized by the normal current flow through said loop, indicator mechanism having a plurality of electromagnets, a second test loop connected to said auxiliary stations and so serially including the 105 indicator magnets that said indicator magnets are not effectively energized by the normal current flow through said loop, current supply mechanism for said loops, and alarm mechanism so connected with said loops as to 110 be rendered active by a break in either of said loops.

20. In an auxiliary alarm system: a box starting magnet, a plurality of auxiliary stations, a test loop connected to said auxiliary stations and including the box starting magnet, indicator mechanism having a plurality of electromagnets, a second test loop connected to said auxiliary stations and so serially including the indicator magnets 115 120 that certain of said magnets are effectively energized by the current flow through said loop when said loops are connected by the operation of any auxiliary station, current mechanism for said loops, and alarm mechanism so connected with said loops as to be rendered active by a break in either of said loops. 125

21. In an auxiliary alarm system: a box starting magnet; a plurality of auxiliary 130

stations; a test loop connected to said auxiliary stations and including the box starting magnet; indicator mechanism having a plurality of electromagnets; a second test loop connected to said auxiliary stations and so serially including the indicator magnets that said magnets are not effectively energized by the normal current flow through said loop, and certain of said magnets are effectively energized by the current flow through said loop when said loops are connected by the operation of any auxiliary station; current supply mechanism for said loops; and alarm mechanism so connected with said loops as to be rendered active by a break in either of said loops.

22. In an auxiliary alarm system: a box starting magnet; a plurality of auxiliary stations; a test loop connected to said auxiliary stations and including the box starting magnet; indicator mechanism having a

plurality of electromagnets; a second test loop connected to said auxiliary stations and so serially including the indicator magnets that said magnets are not effectively energized by current flow through said loop only, and certain of said magnets are effectively energized by current flow resulting from the establishment of a connection between certain conductors of said loop and the other test loop; current supply mechanism for said loops; and alarm mechanism so connected with said loops as to be rendered active by a break in either of said loops.

In witness whereof, I hereunto subscribe my name, this 22nd day of September, A. D. 1914.

C. E. BEACH.

Witnesses:

M. L. THOMAS,
D. W. FOSTER.
